UNITED STATES PATENT OFFICE.

ARVID EMANUEL KARLBERG AND MARSHALL BIDWELL SARGENT, OF OWENSBORO, KENTUCKY, ASSIGNORS TO THE STENOTYPE COMPANY, OF INDIANAPOLIS, INDIANA.

REWINDING MECHANISM FOR TYPE-WRITING MACHINES.

1,105,082.

Specification of Letters Patent. Patented July 28, 1914.

Application filed April 7, 1914. Serial No. 830,317.

To all whom it may concern:

Be it known that we, ARVID E. KARLBERG and MARSHALL B. SARGENT, citizens of the United States, and residents of Owensboro, 5 in the county of Daviess and State of Kentucky, have invented certain new and useful Improvements in Rewinding Mechanism for Type-Writing Machines; and we do hereby declare the following to be a full, clear, and 10 exact description of the invention, such as will enable others skilled in the art to which it appertains to make and use the same.

This invention relates to improvements in 15 rewinding mechanism for typewriting machines,—the object of the invention being to provide simple and efficient mechanism which will be operable from the paper feed mechanism of a machine of the class employed for stenographic typewriting, to accurately 20 reel the paper strip step-by-step after it leaves the writing mechanism, and to so construct such rewinding means that it may be readily and quickly manipulated manually in such manner as to permit ready 25 retrograde rotation of the rewinding reel when the operator desires to inspect the writing on the reeled paper strip.

With this object in view, the invention 30 consists in certain novel features of construction and combinations of parts as hereinafter set forth and pointed out in the claims.

In the accompanying drawings, Figure 1 35 is a sectional view (partly in elevation) showing the application of our improvements; Fig. 2 is a plan view partly in section; Fig. 3 is a detail view illustrating positions which the parts may assume under different conditions, and Fig. 4 is an enlarged 40 sectional view illustrating the ratchet devices.

1 represents the frame of the machine, wherein is mounted suitable printing means embodying a platen 2 and type bars 3,—the 45 latter being operable by suitably arranged key levers 4. A universal bar 5, operated by the key levers, is connected by an arm 6 and pitman 7 with paper feeding mechanism 8.

A paper strip 9 passes from a supply roll 50 11 and after passing in front of the platen and over guiding devices 12, passes through the paper feed mechanism 8 and it will then

be wound upon a re-winding reel,—the construction and operation of which will now be explained.

Two arms 13—14 are removably attached to the frame 1 by means of thumb screws 15 or in any other suitable manner and project rearwardly from said frame 1, said arms being provided at their rear ends with sleeves 16—17 respectively. A spindle 18 is revolvably mounted in the sleeve 16 and to one end of this spindle, a disk 19 is secured by means of a screw 20, the other end of said spindle being provided with a thumb piece 21. The spindle 18 is also longitudinally movable and is normally pressed in one direction by means of a spring 22 inclosed within the sleeve 16.

A spindle 23 is mounted in the sleeve 17 70 of arm 14 and provided at one end with a thumb piece 24. A disk 25 is secured to the inner end of the spindle 23 by means of a screw 26, and near the head of this screw, the disk 25 is provided with a pin 27. A removable hub or core piece 28 is disposed between the disks and is made hollow or with socketed ends to receive the heads of the screws 20 and 26 and is also notched, as at 75 29 to receive the pin 27 on disk 25, so as to cause the core piece 28 and disk 25 to rotate together. The disks 19 and 25 with the interposed hub or core piece 28 constitute the reel on which the paper coming from the machine is rewound.

A ratchet wheel 30 is rigidly secured centrally to the outer face of the reel disk 25, and adjacent to this ratchet wheel, a disk 31 is mounted loosely on the spindle 23 and provided with a peripheral flange 32 inclosing the ratchet wheel but spaced radially therefrom. A gravity pawl 33 is pivotally attached to the inner face of the disk 31 and its tooth is maintained by gravity, in engagement with the toothed periphery of the ratchet wheel when the parts are disposed in their normal positions, as shown in full lines in Fig. 3. When the disk 31 is turned over, as indicated in dotted lines in Fig. 3, the pawl will drop by gravity from engagement with the ratchet wheel and rest on a pad 33^a secured to the flange 32 of the disk 31. When the ratchet devices are thus disposed, the re-winding reel may be turned backwardly to

permit the free unwinding of the paper when the operator desires to inspect portions of the writing on the paper.

The disk 31 of the ratchet devices is provided with an arm 34 which may be secured to the disk by means of a plate 35 from which said arm projects and which is secured in any suitable manner to the disk 31. A pitman 36 connects the arm 34 with the paper feed mechanism 8, so that the movements of the latter will be transmitted to the ratchet devices for operating the rewinding reel. The pitman 36 comprises two members 37-38 which are pivotally connected together, one of said members being provided with hook 39 which loosely embraces the other member. By thus constructing the pitman, the joint between its sections may be readily broken to permit the shifting of the ratchet devices, as previously explained, from the full line to the dotted line positions in Fig. 3.

Having fully described our invention what we claim as new and desire to secure by Letters-Patent, is:—

1. The combination with typewriting mechanism and a paper rewinding reel, of ratchet devices connected with said reel and comprising a ratchet wheel and a pawl normally resting by gravity over and engaging said ratchet wheel, an abutment for said pawl when the same is disposed under and out of engagement with the ratchet wheel and a pitman comprising jointed sections, connecting said ratchet devices with a movable part of the typewriting mechanism.

2. The combination with typewriting mechanism and a rewinding reel, of a ratchet wheel secured to the rewinding reel, a loosely mounted part, a gravity pawl carried by said loosely mounted part and nor-

mally disposed over and engaging the ratchet wheel, an abutment on said loosely mounted part for the pawl when the latter is disposed under and out of engagement with the ratchet wheel, a pitman comprising jointed sections connecting said loosely mounted part with a movable part of the typewriting mechanism.

3. Rewinding mechanism for typewriting machines, comprising a rewinding reel, a mounting therefor, a ratchet wheel secured to the reel, a part loosely mounted with respect to the reel, a gravity pawl carried by the loosely mounted part and normally disposed over and engaging the ratchet wheel, an abutment for the pawl when it drops by gravity from the ratchet wheel, and an operating pitman connected with said loosely mounted part.

4. Rewinding mechanism for typewriting machines, comprising a reel, a mounting therefrom, a ratchet wheel secured to the reel, a loosely mounted disk having a flange inclosing the ratchet wheel, a gravity pawl carried by said disk and adapted to normally project over the ratchet wheel and engage the same, the flange of said disk constituting an abutment for the free end of the pawl when the disk is turned to dispose said pawl under and out of engagement with the ratchet wheel, an arm projecting from said disk, and an operating pitman connected with said arm.

In testimony whereof, we have signed this specification in the presence of two subscribing witnesses.

ARVID EMANUEL KARLBERG.
MARSHALL BIDWELL SARGENT.
